UNITED STATES PATENT OFFICE

FRANCIS H. TREAT, OF BELLEVUE, OHIO, ASSIGNOR TO DUFF PATENTS COMPANY, INC., OF PITTSBURGH, PENNSYLVANIA, A CORPORATION OF PENNSYLVANIA

BLAST-DISTRIBUTING MEANS FOR GAS PRODUCERS

Original application filed May 25, 1920, Serial No. 384,053. Divided and this application filed August 29, 1923. Serial No. 659,857.

The present invention relates broadly to gas producers, and more particularly to blast distributing means therefor, the present application being a division of my co-pending application Serial No. 384,053, filed May 25, 1920, Patent No. 1,469,399, October 2, 1923.

In gas producer practice, particularly in this country, the kind of fuel universally used is a bituminous coal having a decided caking nature or tendency to become pasty and sticky when it is heated to a temperature corresponding to that usually existing in the upper portion of the fuel bed of the gas producer.

15 In accordance with the dictates of good gas producer practice, the fuel bed should not exceed about three feet in depth and its depth and the rate of combustion of the fuel should be maintained substantially uniform throughout its horizontal extent, to the end that the established standards as to quality and quantity of production may be maintained.

By reason of the fact that in the air blast is 25 comprised the active element for the gasification of the fuel, it is essential, in order to secure the desired uniformity of combustion, that means be provided to insure a uniform distribution of the blast throughout the horizontal extent of the fuel bed. This is particularly important in the case of modern gas producers in which the diameter of the fuel bed is most commonly from ten to eleven feet.

35 Accompanying a uniform combustion of the fuel will be a correspondingly uniform production of ashes throughout the horizontal extent of the fuel bed. It is important therefore that the descent of these ashes from the fuel bed into the ash pan be not impeded to such an extent as to cause them to accumulate and extend into the fuel zone, thereby interfering with the combustion.

An object of the present invention therefore is to provide means for the uniform distribution of the blast, with positive effect, substantially throughout the horizontal extent of the fuel bed of a gas producer.

45 A further object of the invention is to provide in a gas producer an arrangement of

air blast distributing tuyères in lieu of the usual grate construction, the said tuyères being so constructed and arranged as to impose a minimum resistance to the descent of the ashes from the fuel bed.

55 In the accompanying drawings, there is shown, for purposes of illustration only, one embodiment of the present invention, it being understood that the drawings do not define the limits of the invention as changes 60 may be made in the general construction and operation therein disclosed without departing from the spirit of the invention or scope of my broader claims.

65 In the drawings—
Figure 1 is a view, partly in vertical section and partly in side elevation, of a gas producer embodying my invention.

70 Figure 2 is a plan view, partly in section, of the parts shown in Figure 1.

Figure 3 is a central vertical sectional view of the lower portion of the gas producer; and

75 Figure 4 is a cross-sectional view of one of the tuyères.

I have illustrated my invention in connection with a gas producer of the type disclosed in my patent previously referred to. This producer comprises a shell 2 having the usual refractory lining. The shell is supported by means of columns 3, preferably of structural steel. The bases of these columns are offset sufficiently so as not to interfere with the producer shell and the ash pan and associated parts, the upper portions of the columns being bent inwardly and secured to the shell by means of plates 4.

Beneath the shell is a stationary ash pan 5 mounted on suitable supports 6 and into which a mantle or apron 7 depends to a distance below the water level of the pan sufficient to provide the usual water seal. The ash pan is provided with an upstanding edge 8 whereby the pan may hold the desired amount of water.

90 Two rotary scrapers 9 are arranged to turn within the ash pan and to deliver ashes over the peripheral edge thereof. These scrapers are arranged oppositely to each other so as to give a balanced action. They 100

are preferably of a spiral or curved form, approximately as shown, their inner ends being secured to a central hub 10. This hub is loosely mounted around the centrally fixed water discharge pipe 11 which extends upwardly into the pan and within the cap 12, a plurality of openings 13 being provided through which the water can enter said cap and thence pass into the discharge pipe. 5 From the hub out to a point adjacent to the periphery of the bottom of the pan the scrapers consist of flat sections which are arranged to rotate adjacent to the bottom of the pan. At this point they merge into the 10 inclined portions 14 which extend obliquely upward along the sloping sides of the pan and to the outer periphery of its upper edge. The ends of the portions 14 are rigidly secured to posts 15 which at their lower ends 15 are secured to the inner side of an annular ring 16 which surrounds the pan. This ring is mounted on a plurality of wheels 17 journaled therein and which travel on a circular track 18. A portion of the outer periphery of the ring is formed with gear teeth 19 which are engaged by driving pinions 20. These driving pinions are journaled at the upper ends of short vertical shafts 21. Each of these shafts carries a bevel wheel 22 which meshes with a bevel pinion 23 on a diametrically extending shaft 24 driven by any suitable means, such as an electric motor 25. From the foregoing it will be apparent that the ring 16 and the scrapers 9 rotate as a 20 unit with respect to the stationary pan.

An ash receiving trough 26 is mounted on the upper peripheral portions of the wheels 17 in such a manner as to be rotated around the ash pan by said wheels. This trough is arranged to receive the ashes which are discharged over the upper edge of the pan by the action of the scrapers. The ashes are discharged from this trough at a single point by means of a suitable plow 27 supported by a fixed frame member 28 secured to and depending from the shell 2.

Having described the general construction and arrangement of the producer, I will now proceed to describe the novel tuyère system of blast distribution which constitutes a preferred embodiment of my invention. These tuyères, indicated by the reference numeral 29, project inwardly through the depending mantle or apron 7 at the base of the producer shell and are removably seated in openings therein and supported by brackets 30 secured to the inner side of the apron or mantle. Each tuyère is also preferably provided with a downwardly projecting flange 31 which engages the outer face of the apron or mantle. 55

It will be seen, by reference to Figure 2, that these tuyères are uniformly spaced around the periphery of the base of the shell 2 at distances preferably less than 90 degrees apart and project radially inwardly,

toward the axis of the shell, their lengths being materially less than the radius of the producer in the plane of their location, so as to leave an open unobstructed central area in the producer at this point. These tuyères extend in a horizontal plane beneath the fuel bed and divide the latter into a plurality of equal sectors each of which is traversed by its own air blast conduit which is centrally located therein, the larger fuel bed thereby being divided into a group of small ones each having an independent air blast supply. 70 75

In the particular form shown, these tuyères are of circular cross-section and each is provided at its lower side with blast orifices 32 arranged in two longitudinal rows preferably at opposite sides of a vertical plane containing the longitudinal axis of the tuyère. The tuyères are of inwardly decreasing cross-sectional area whereby a substantially uniform air velocity may be maintained therealong. The inner end of each tuyère is provided with a downwardly and inwardly extending discharge opening 33. Each tuyère may be supplied with air blast by any suitable arrangement such as a steam jet blower 34 of any well known character. It will be apparent that the blast orifices 32 and 33 may be so proportioned as to correspond with the portion of the sector of the fuel bed to which they are tributary and thereby supply the blast equally to all parts of such sector with an amount of horizontal travel which may be considered a negligible quantity. Moreover, as each tuyère may be tapered so that its diameter will correspond with the quantity of the air blast passing a given point, its diameter may be reduced to very small proportions, and said tuyère, in addition, being provided with a curved top, the entire series of tuyères will offer a minimum resistance to the free passage of the ashes downwardly between them while giving a very effective distribution of the blast. 100 105

From the foregoing, the advantages arising from my invention will be apparent to those skilled in the art. By the provision of means of the character described extending in a horizontal plane underlying the fuel bed and effective to secure a uniform blast action throughout the same, it must necessarily follow that with an equally uniform removal of the ashes from beneath said means and with a proper distribution of the fuel to the fuel bed, the plane which marks the division between the ash and the fuel zones of the producer may be continuously maintained at an elevation which is equal at all points and the thickness of the fuel bed may be maintained continuously uniform throughout, to the end that the highest standards governing the quality and quantity of production may be attained. 110 115 120 125

I claim:

1. A gas producer having a chamber with 130

stationary walls adapted to contain a fuel bed, a series of blast tuyères supported on the stationary inside wall of the producer at regularly spaced intervals thereabout, said tuyères extending radially into the producer from the side walls thereof in a substantially horizontal plane and being of a length materially less than the radius of the fuel chamber in the plane in which they are located, whereby an open central area is provided, said tuyères being of inwardly decreasing cross sectional area and having openings therealong and at the inner ends thereof whereby they supply air to the fuel bed which they traverse and to the open central area of the fuel bed, the said tuyères being located at intervals less than 90° apart whereby each tuyère supplies air to only a relatively small sector of the fuel bed, the decrease in the cross sectional area of the tuyères securing the necessary velocity at the inner ends of the tuyères to project a jet of air from said openings at their inner ends, said decrease in cross sectional area of the tuyères also securing maximum spacing between the ends of the convergent tuyères.

2. A gas producer having a chamber adapted to contain a fuel bed, a series of blast tuyères projecting through the wall of the chamber and extending inwardly from the wall toward the center of the chamber, said tuyères being of less length than the radius of the producer in the plane in which they are located, and extending into the fuel bed in a substantially horizontal plane, said tuyères being inwardly tapered and, having downwardly turned inner ends, the downwardly turned ends of the tuyères having air discharge openings therein for projecting a blast of air downwardly and inwardly toward the central portion of the fuel bed, said tuyères also being provided with downwardly directed openings at intervals along their length.

3. A gas producer having a chamber adapted to contain a fuel bed, a series of radially disposed blast tuyères in the fuel bed extending inwardly from the wall of the chamber part way to the center thereof in a substantially horizontal direction, each tuyère having a discharge opening at its inner end, the discharge opening at the end of each tuyère being protected by an overhanging extension of the tuyère whereby said tuyères project a jet of air toward the center of the tuyère and the opening at the end of each tuyère is protected from having ash or fuel jammed against it, said tuyères being tapered toward their inner ends and having discharge openings therein intermediate the ends thereof and located on an under surface of the tuyère, said tuyères being located less than 90° apart and being spaced at substantially equal intervals from each other.

4. In a gas producer, a horizontally extending blast tuyère comprising an elongated hol-

low body of decreasing cross sectional area toward one end, and having a discharge port at the smaller end thereof protected by an overhang at the end of the tuyère, said body having a solid top portion and discharge openings therein at intervals along its length, the decreasing cross sectional area of the tuyère assuring substantially uniform distribution of air therealong and securing a desired velocity for the jet of air projected from the downwardly turned end thereof.

5. In a gas producer, a radially extending blast tuyère comprising an elongated hollow body of decreasing cross sectional area toward one end and having a downwardly turned discharge portion at the smaller end thereof, said body having discharge openings therein at intervals along its length intermediate the ends thereof, said discharge openings being located on the under side only of the body at each side of the longitudinal axis thereof.

In testimony whereof I have hereunto set my hand.
